ERASER

Herbert G. Lehmann, Bridgeport, Conn.

Application June 18, 1947, Serial No. 755,323

6 Claims. (Cl. 120—36)

1

This invention relates to renewable and refillable erasers having rubber or rubber-like elements for rubbing out ink and pencil marks and the like.

An object of the invention is to provide an improved refillable eraser of the type having a flat, broad and thin rubber element, which is extremely simple in construction and economical to manufacture, yet is effective and efficient in use.

A further object of the invention is to provide an improved eraser as above, which is so organized that the working end portion of the rubber element is securely gripped against slipping or shifting without the likelihood of its being cut into or breaking away, yet the element may be quickly released and advanced when it becomes worn.

Another object of the invention is to provide an improved eraser as characterized above, which is extremely sturdy and strong so that it will withstand all pressures and forces encountered in use, without flexing, bending or deforming.

Still another object of the invention is to provide an improved eraser of the type having two separable clamping portions acting also as a holder, and having a slide band drawing together the two clamping portions, wherein releasing movement of the slide band enables the clamping portions to separate a substantial amount sufficient to thoroughly free the rubber element and wherein the clamping portions are securely locked against separation when drawn together by the band, thereby preventing inadvertent loosening of the rubber element.

In accomplishing these objects there is provided by the invention a novel holder structure comprising a single strip of sheet metal bent at its center into a U-shape, one of the legs of the U being substantially flat and the other leg having side flanges producing a channel shape adapted to receive the flat leg. The legs at their unjoined ends are embossed or formed into novel structures which are cooperable with each other and with a novel slide band to provide an improved, efficient and effective means for clamping and holding a flat, slab-like rubber eraser element.

One leg has a pair of spaced, parallel, longitudinally extending ribs of generally uniform height embossed in it, the ribs projecting outward from the outside of the leg, and has a single nib embossed in it and projecting inwardly from the inside of the leg, the nib being located between the ribs and closely adjacent the end of the leg. The other leg end has a single, centralized longitudinally extending outwardly pro-

2

jecting rib embossed in it, and on opposite sides of the rib has a pair of nibs projecting inwardly from the inside of the leg, the said nibs being located closely adjacent the end of the leg also.

5 The slide band comprises a single strip of flat metal stock bent to have the shape of a generally flat band of substantially rectangular configuration, one side of the band being discontinuous, that is, having a cut transversely across it at its center, where the ends of the strip terminate. The slide band is of a size to closely fit to and be slidable over the U-shaped holder, and is placed on the holder so that the cut in the band provides clearance for the single rib of the leg end when the band is at said end. For this location of the band the two ribs of the other leg end engage the opposite side of the band, and as a result the leg ends are forced together, clamping between them the rubber element.

10 20 The embossed nibs of the leg ends embed themselves in the rubber element until the flat insides of the legs become engaged with the element, and since the nibs are staggered the element is not deeply cut into at any one point nor can it be broken away, while at the same time the working end portion of the element is securely held against slipping or shifting.

25 30 By virtue of the strengthening effect of the ribs and the flanges of the legs, the slide band can be made to exert considerable pressure on the rubber element without deformation of the legs or danger of breaking away of the rubber. When the slide band is shifted off the ribs, the leg ends may be separated sufficiently to completely free the rubber element for advance or replacement, and by virtue of the uniform height of the ribs no camming action is present to tend to inadvertently shift the band off the ribs, therefore the legs are securely locked together when the band is in locking position.

35 40 To function as stops for the slide band, the two ribs on the one leg end are formed to have raised portions or protuberances which prevent the band from being slid off the end of the holder and locate it in proper locking position; thus, besides the rubber erasing element, the holder device of this invention comprises but two pieces, which are of simple and economical construction and which do not require assembly operations other than placing one over the other, and therefore the device may be inexpensively produced.

45 Other features and advantages will herein-after appear.

50 55 In the accompanying drawings:
Figure 1 is a top or plan view of the eraser of this invention.

3

Fig. 2 is a side elevation of the eraser.
 Fig. 3 is an underside view of the eraser.
 Fig. 4 is a perspective view of the slide band.
 Fig. 5 is a transverse section taken on line 5—5 of Fig. 3.

Fig. 6 is a transverse section taken on line 6—6 of Fig. 3, and

Fig. 7 is a plan view of the rubber eraser element.

As shown, the improved eraser of the present invention comprises essentially a rubber or rubber-like eraser element 10, a body or holder 11 for the element, and a slide band clamping means 12.

The eraser element 10 is in the form of a flat strip or slab of uniform width and thickness, and when unused has substantial length so as to occupy practically the entire length of the holder 11. The holder 11 is formed from a single flat strip of sheet metal bent at its center, as indicated at 13, to a U-shape providing two legs 14 and 15 which are coextensive with and broadside to each other.

The leg 14 has downturned flanges 16 along its opposite side edges, thereby providing a channel shape, and the leg 15 is generally flat and of a width to be received snugly between the flanges 16 as shown in Figs. 2 and 3. The cross sectional dimensions of the rubber eraser element 10 are such as to enable the element to be snugly received between the legs 14 and 15 of the holder 11 and between the flanges 16 as shown in Fig. 6.

According to the invention the unjoined end portions of the legs 14 and 15 are embossed or formed into novel structures which are cooperable with a novel slide band, to be described later, whereby an effective and efficient means is provided for clamping and holding the eraser element 10. Referring to Figs. 1 and 6 the leg 14 has a centralized, longitudinally extending rib 17 which projects outwardly from the outside of the leg, and which is of substantially uniform height except at its ends where it tapers and blends with the flat surface of the leg. The rib 17 extends practically to the end of the leg 14 and acts to considerably stiffen the leg end.

At the end of the leg 14 and on opposite sides of the rib 17 a pair of nibs 18 are provided, projecting inwardly from the inside of the leg, see Figs. 1 and 5. Adjacent the nibs 18 the corners 19 of the leg 14 are rounded or provided with a radius, as shown in Fig. 1. At the end of the leg 15 a pair of spaced, parallel, longitudinally extending ribs 20 of generally uniform height are formed, the ribs projecting outwardly from the outside of the leg and being coextensive with the rib 17 thereby to extend practically to the end of the leg 15. The ribs 20 are formed to have projections 21 intermediate their ends, which function as stops for the slide band 12.

Between the ribs 20 and closely adjacent the end of the leg 15 a nib 23 is formed, Figs. 3 and 5, which projects inwardly from the inside of the leg. The ribs 23 serve to considerably stiffen the end of the leg 15, and this is of considerable importance as the leg is otherwise devoid of side flanges, being a flat strip of thin metal which may be easily bent.

The slide band 12 provided by the invention for the purpose of drawing together the legs 14 and 15 of the holder 11, has a novel shape as clearly shown in Fig. 4. The band 12 comprises a single strip of flat metal stock bent to have the shape of a generally flat band, with end portions 22, a continuous side portion 23 and a discontinuous

4

side portion consisting of the ends 24 of the strip. The side portion 23 of the band 12 has slight bends at 25, Figs. 3 and 4, the said bends being spaced apart the same distance as the ribs 20 of the leg 15. The slide band 12 is of a shape and size to closely fit over the legs 14 and 15 of the holder 11, and is placed on the holder so that the cut in the band clears the single rib 17 of the leg 14 when the band is in locking position, as shown in Fig. 1. When the band 12 is so located, the side portion 23 thereof engages the ribs 20 of the leg 15, as shown in Figs. 3 and 6, and this causes the legs to be forced together so that the inner sides thereof engage and firmly grip the rubber eraser element 10.

For such clamping of the element 10 the nibs 18 and 23 serve an important function. As shown in Fig. 5 the nibs are embedded in the element 10, and as seen in Figs. 1 and 3, they grip the element closely adjacent the working end thereof, and therefore they serve to hold the said working end firmly and securely against sliding or shifting. During use of the eraser the working end of the element 10 is subjected to considerable force at times, tending to shift it in the holder 11. I have found, however, that the provision of the nibs 18 and 23, together with the stiffening ribs 17 and 20 and the band 12, effectively hold the element 10 against shifting, and at the same time the element is not cut into, and does not tend to break away during use. In connection with this latter, the staggered locations of the nibs 18 and 23 play an important part, and also the substantial pressure of the inner sides of the legs 14 and 15 on the element, as made possible in part by the strengthening effect of the ribs 17 and 20 in the neighborhood of the nibs.

Moreover, due to the substantially uniform height of the ribs 20 there is absent any tendency for the slide band 12 to be inadvertently shifted off the ribs by a camming action, and therefore the legs 14 and 15 are at all times securely locked together, and the element 10 is securely held in working position.

When it is desired to advance the rubber element 10 or replace it, the slide band 12 is merely pushed toward the center of the holder 11, off the ribs 20, whereupon the leg 15 may be separated from the leg 14 sufficiently to free the element. For this purpose the leg 15, being flat, may be flexed when the band 12 is retracted, yet in use the holder 11 is extremely rigid, and this is an important feature.

As shown in Fig. 6, the ribs 20 engage the band 12 at the bends in the side portion 23 thereof, thereby making the structure more compact and enabling the band to exert a stronger pressure with less tendency to yield, on the legs 14 and 15.

By virtue of the provision of the single strengthening rib 17 in the leg 14, and the cut in the discontinuous side of the band 12, an extremely simple band construction is made possible while at the same time a strong and sturdy organization is had. It will be seen that but few and simple parts are required in the eraser of this invention, the parts being inexpensive to fabricate, and that assembly costs have been reduced to a minimum by the one-piece holder structure. In assembling the device, prior to insertion of the rubber element 10 between the legs 14 and 15, the slide band is placed over the holder, and this is accomplished easily and quickly by first moving the leg 15 inwardly between the flanges 16 and against the leg 14, there-

by providing considerable clearance between the ribs 20 and the side portion 23 of the band.

For the purpose of making the advancing or feeding of the element 10 easier when the legs 14 and 15 are released, the said legs have aligned and coextensive slots 26, Figs. 1 and 3, through which the element 10 may be grasped. The slide band 12 is prevented from sliding off the folded end of the holder 11 by a nib 27, Figs. 2 and 3, formed in the leg 15 and projecting therefrom. The unjoined end of the leg 15 is provided with rounded corners adjacent the ends of the ribs 20, as shown in Fig. 3, so that the corner portions of the element 10 are available for use without danger of scratching the paper being worked on.

Variations and modifications may be made within the scope of this invention, and portions of the improvements may be used without others.

I claim:

1. A holder for a thin elongate slab of erasing material, comprising a pair of opposed, elongate, coextensive, flat, sheet metal strips disposed broadside to each other and connected together at one pair of corresponding ends, the inner sides of the unconnected ends having projecting nibs located closely adjacent but spaced from the end edges thereof for embedment into opposite sides of the slab of erasing material adjacent the working end of the slab to prevent edgewise movement of the working end, and said strips having longitudinal reinforcing ribs extending from points alongside the nibs toward the said connected ends; a releasable slide band engaging said ribs at points removed from the said nibs, for clamping together the unconnected ends of the strips; and stop means maintaining said band spaced, longitudinally of the strip, away from said nibs.

2. A holder for a thin elongate slab of erasing material, comprising a pair of opposed, elongate, coextensive, flat, sheet metal strips disposed broadside to each other and connected together at one pair of corresponding ends, the unconnected end of one strip having a pair of longitudinally extending reinforcing ribs projecting from its outer surface, and having a nib located between the ribs and closely adjacent the end edge, projecting from its inner surface, and the unconnected end of the other strip having a centralized longitudinally extending reinforcing rib projecting from its outer surface, and having a pair of nibs located on opposite sides of the rib and closely adjacent the end edge, projecting from its inner surface; and releasable means engaging the unconnected ends of the strips for clamping the said ends together on opposite sides of the slab of erasing material.

3. A holder for a thin elongate slab of erasing material, comprising a pair of opposed, elongate, coextensive, flat, sheet metal strips disposed broadside to each other and connected together at one pair of corresponding ends, the unconnected end of one strip having a pair of longitudinally extending reinforcing ribs projecting from its outer surface, and having a nib located between the ribs and closely adjacent the end edge, projecting from its inner surface, and the unconnected end of the other strip having a centralized longitudinally extending reinforcing rib projecting from its outer surface, and having a

pair of nibs located on opposite sides of the rib and closely adjacent the end edge, projecting from its inner surface; and a slide band having a cut in one side portion, said band engaging the unconnected ends of the strips and the cut in the band providing clearance for the said centralized rib on the other strip.

4. A holder for a thin elongate slab of erasing material, comprising a pair of opposed, elongate, coextensive, sheet metal plates disposed broadside to each other and connected together at one pair of corresponding ends, said plates being adapted to receive between them the said slab of erasing material, one of said plates having means for maintaining it rigid longitudinally and the other plate being relatively flexible longitudinally and having at its unconnected end a longitudinally extending reinforcing rib projecting from its outer surface; a slide band carried by the plates and slidable longitudinally thereof for clamping and releasing the said slab, said band having a cut in one side portion, providing clearance for the rib of the flexible strip; and means for limiting movement of the slide band toward the connected ends of the plates, said flexible plate being bendable to release the said slab when the slide band movement is limited by said means.

5. A holder for a thin elongate slab of erasing material, comprising a pair of opposed, elongate, coextensive, sheet metal plates disposed broadside to each other and connected together at one pair of corresponding ends, said plates being adapted to receive between them the said slab of erasing material and one of said plates having at its unconnected end a longitudinally extending reinforcing rib projecting from its outer surface; and a slide band carried by the plates and slidable longitudinally thereof for clamping and releasing the said slab, said band having a cut in one side portion, providing clearance for the said reinforcing rib.

6. A holder for a thin elongate slab of erasing material, comprising a pair of opposed, elongate, coextensive, flat, sheet metal strips disposed broadside to each other and connected together at one pair of corresponding ends, the unconnected end of one strip having a pair of longitudinally extending reinforcing ribs projecting from its outer surface, and the unconnected end of the other strip having a centralized longitudinally extending reinforcing rib projecting from its outer surface; and a slide band having a cut in one side portion, said band being slidable over the strips and engageable with the said pair of ribs, and the cut in the band providing clearance for the said centralized rib.
